UNITED STATES PATENT OFFICE

154,071

DESIGN FOR A VEGETABLE CUTTER

Frederick R. Smith, Toledo, Ohio

Application May 28, 1947, Serial No. 139,319

Term of patent 14 years

(Cl. D89—1)

To all whom it may concern:

Be it known that I, Frederick R. Smith, a citizen of the United States, residing at Toledo, county of Lucas, and State of Ohio, have invented a new, original, and ornamental Design for a Vegetable Cutter, of which the following is a specification, reference being had to the accompanying drawings, forming part thereof.

In the drawing,

Figure 1 is a top plan view of the vegetable cutter, showing my new design;

Figure 2 is a side view of the vegetable cutter shown in Figure 1;

Figure 3 is an end view of the vegetable cutter; and

Figure 4 is a fragmentary sectional view taken substantially on the line 4—4 of Figure 1.

My design for vegetable cutter is characterized by a parallelogrammatically shaped frame and

laterally extending handle portions of the configuration and proportions shown in the drawing.

I claim:

The ornamental design for a vegetable cutter, substantially as shown and described.

FREDERICK R. SMITH.
